PAINTBRUSH HOLDER

Raymond Zegers, Evanston, Ill.

Application June 22, 1950, Serial No. 169,737

7 Claims. (Cl. 206—15.1)

1

This invention relates to brush holders and, more particularly, to brush holders of the type especially well adapted for storing and carrying paint brushes, and the like.

As is well known to those skilled in the art, proper storing and preserving of paint brushes not in use has always been a major problem, and various methods and devices for storing paint brushes so as to preserve the desired soft texture of the bristles have heretofore been attempted.

However, the various methods of storing paint brushes heretofore known in the art, have had several inherent disadvantages, such as, for example, being inefficient and ineffective in operation; being cumbersome and awkward to use and store; deforming the bristles of the stored brushes from their natural shapes or positions; requiring that the containers in which the brushes are stored be inspected at relatively regular intervals so that the cleaning fluid lost through evaporation and the like, may be restored; and not affording a brush holder which the workman could readily use for transporting the brush being stored.

It is a primary object of my invention to afford a novel brush holder which overcomes the disadvantages of brush holders and storing devices heretofore known in the art.

Another important object of my invention is to afford a novel brush holder wherein the parts thereof are constituted and arranged in a novel and expeditious manner to afford a novel, efficient, and practical storage receptacle and carrying case for paint brushes, and the like, wherein the shape and texture of the bristles of a brush may be effectively preserved during both storage and transporting of a brush therein.

Another object of my invention is to afford a relatively light brush holder of a size and shape substantially the same as the brush, being only slightly larger in outline than the brush, so that the holder may be effectively used by a painter for transporting the brush to and from the job, and, when so used, may be readily carried in the painter's hand, pocket, tool box, or the like.

A further object is to afford a novel brush holder of the aforementioned type which automatically and firmly holds the bristles of a paint brush being stored therein in compact, flat, substantially natural position to thereby preserve the desired shape and arrangement of the bristles of the brush.

Yet another object is to afford a brush holder of the aforementioned type wherein the brush is sealed therein in a novel and expeditious man-

2

ner, and the desired pliability of the bristles may be readily preserved for a prolonged period by a small quantity of turpentine, or the like, placed in the brush holder as a preservative and softening agent for the bristles.

As will be appreciated by those skilled in the art, various types of cleaning agents or softening agents are used to clean and preserve brushes used for applying different types of coatings. 10 Thus, for example, in cleaning and preserving brushes used with the usual oil paints, and the like, solvents such as turpentine are commonly used for cleaning the brushes; and in cleaning brushes used for applying shellac, alcohol is the common solvent used. It will be remembered that herein, in referring to turpentine, alcohol, or other cleansing preservative, or softening agents, reference is made to such specific agents only by way of illustration and not by way of 15 limitation and that other agents may be used without departing from the purview of my invention, an important object of my invention being to provide a brush holder wherein softening agents of either high or low volatility may be used and will be effectively retained in the holder over prolonged periods of time.

A further object of my invention is to afford a brush holder of the aforementioned type having a removable cover which may be quickly and easily removed from and replaced on the brush holder and which, when removed from the brush holder affords an opening through which a paint brush, or the like, may be readily inserted into, and removed from, stored position in the holder. 30

Another object is to afford a brush holder of the aforementioned type wherein the cover member is firmly held in a novel and expeditious manner in sealed relation to the body portion of the brush holder when disposed in closed position 35 thereon and, wherein, when the cover member is in closed position, the brush holder is substantially air-tight and is sealed against the spilling or evaporation of cleaning or preserving liquid enclosed in the holder.

Another object is to provide a brush holder of the aforementioned type wherein the cover member is held in closed position on the body member in a novel and expeditious manner by force applied to the outwardly facing central portion of 40 the cover member.

An object ancillary to the foregoing is to provide a brush holder of the aforementioned type wherein the cover member is releasably held in closed position on the body member thereof by 45 hinged retaining means which spring-urge the

cover member into closed position on the body member, and which may be quickly and easily disposed in retaining position relative to the cover member, and, in addition, may be quickly and easily disposed in released position relative to the cover member to thereby free the cover member for removal from the body member.

Another object is to provide a brush holder of the aforementioned type which affords a practical, economical storing container for paint brushes, and the like, wherein the shape and pliability of the bristles of paint brushes stored therein may be preserved in a novel and expeditious manner, and wherein the brush is effectively retained in proper stored position therein.

Other and further objects of the present invention will be apparent from the following description and claims and are illustrated in the accompanying drawings which, by way of illustration, show a preferred embodiment of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a top plan view of the preferred form of a brush holder embodying the principles of my invention;

Fig. 2 is a longitudinal sectional view taken substantially along the line 2—2 in Fig. 1;

Fig. 3 is a sectional view taken substantially along the line 3—3 in Fig. 2;

Fig. 4 is an enlarged detail sectional view similar to Fig. 3 but showing certain parts of the brush holder in a different position;

Fig. 5 is a detail elevational view looking in the direction of the arrows 5—5 in Fig. 3;

Fig. 6 is a detail plan view of a portion of the mechanism shown in Fig. 1;

Figs. 7 and 8 are detail sectional views taken substantially on the lines 7—7 and 8—8, respectively, in Fig. 4;

Fig. 9 is a top plan view of a brush holder similar to Fig. 1, but showing a modified form of my invention;

Fig. 10 is a longitudinal sectional view taken substantially along the line 10—10 in Fig. 9;

Fig. 11 is a sectional view taken substantially along the line 11—11 in Fig. 10;

Fig. 12 is a detail plan view of a portion of the mechanism shown in Fig. 9;

Fig. 13 is a detail sectional view taken substantially on the line 13—13 in Fig. 12;

Fig. 14 is a detail sectional view somewhat similar to Fig. 13, but showing the parts therein in a different operative position; and

Fig. 15 is an elevational view taken substantially along the line 15—15 in Fig. 14.

In Figs. 1 to 8, inclusive, of the drawings, a brush holder 20, embodying the principles of my invention, is shown to illustrate a preferred embodiment of my invention. The brush holder 20 comprises, in general, a body member 22, Figs. 1 and 2, having an opening 23 in one side thereof in which a cover member 25 may be removably mounted in operative position, a retainer 26, mounted on the body member 22 being effective to releasably hold the cover member 25 in the operative position.

The body member 22 of the brush holder 20

comprises a bottom wall 28, two end walls 29 and 30, two side walls 32 and 33, and a top wall 35 which is removably mounted on the upper edge portions of the side walls 32 and 33, and the end wall 30, the upper edge portions of the side walls 32 and 33 and the end wall 30 being rabbeted to receive the peripheral edge portion of the top wall 35, and the top wall 35 being secured to the side walls 32 and 33, and the end wall 30 by suitable means such as screws 31. A suitable gasket 38 is disposed between the peripheral edge portion of the top wall 35, and the rabbeted upper edge portions of the side walls 32 and 33 and the end wall 30, to thereby seal the interconnection of the top wall 35 with the end wall 30 and the side walls 32 and 33.

As is best seen in Figs. 1 and 2, the body member 22 of the brush holder 20, is of substantially the same shape and contour as a paint brush, the end portion thereof adjacent to the end wall 30 being relatively narrow to afford a handle portion 41, within which the handle H of a paint brush B, Fig. 2, may be disposed in relatively close fitting relation, and the end portion of the body member 22 adjacent to the end wall 29 flaring outwardly to afford a head portion 42 within which the head portion P of the brush B may be disposed in substantially close fitting relation.

The opening 23 in the body member 22 extends across the entire side of the head portion 42 of the body member 22 opposite the bottom wall 28 and projects a short distance into the handle portion 41 toward the end wall 30, Figs. 1 and 2, to thereby afford an opening through which a brush such as the paint brush B may be quickly and easily inserted into, and removed from, the chamber defined by the walls 28, 29, 30, 32, 33 and 35 of the body member 22. The upper edge portion of the side walls 32 and 33, and the end wall 29, and the inner edge portion 36 of the top wall 35, are rabbeted to afford inwardly projecting ledges 44 surrounding the opening 23 for supporting the cover member 25. The cover member 25 is complementary in size and shape to the opening 23, and is adapted to be mounted on the ledges 44 in close fitting relation to the portions of the side walls 32 and 33, the end wall 29, and the top wall 35, defining the opening 23. Suitable sealing means such as a gasket 73 is mounted on the ledge 44 for engagement with the peripheral edge portion of the cover 25. It will be seen that the gasket 38 and the gasket 73 may each be made as individual unitary pieces.

Two bosses or lugs 46 and 48 project outwardly from the upper edge portions of the side walls 32 and 33, respectively, substantially centrally of the longitudinal edge portion of the head portion 42 of the body member 22, Figs. 1 and 3. Two slots or recesses 47 and 49 are formed in the upper end portion of the bosses 46 and 48, respectively, and are adapted to receive respective end portions of the retaining member 26 as will be discussed in greater detail presently.

The retaining member 26 is substantially in the form of a bale, Figs. 1 and 3, which, when disposed in latching position, extends transversely across the opening 23 between the side walls 32 and 33. As is best seen in Figs. 1 and 3, the retaining member 26 comprises two end sections or brackets 51 and 52, Figs. 1 and 3, and a latching member 53 rotatably mounted therebetween. The two end sections 51 and 52 are preferably formed of spring-steel in the shape of wires each having a loop 55 and 54 at one end thereof, and an upwardly projecting flange or ear 58 and 59 formed at the other end thereof, respectively.

The brackets 51 and 52 of the retaining member 26 are pivotally mounted in the slots 47 and 49 on pins 56 and 57, Fig. 1, which are mounted in the bosses 46 and 48 and extend through the loops 55 and 54 on the brackets 51 and 52, respectively.

The latching member 53 comprises a cam disc or plate 64 eccentrically mounted on a bolt 61 journaled in the ear 59 and retained therein by suitable means such as a nut 62. An elongated handle 65 projects from the disc 64 to provide means for rotating the disc 64 on the bolt 61 as will be presently discussed.

As is best seen in Figs. 3 and 4, the cam disc 64 is held by the bolt 61 in position adjacent to the face of the ear 59 which, when the bracket 52 is disposed in the closed position shown in solid lines in Fig. 3, is disposed adjacent to the ear 58 on the bracket 51. Thus, it will be seen that with both of the brackets 51 and 52 disposed in closed position, as shown in solid lines in Fig. 3, the latching member 53 is supported by the bolt 61 between the ears 58 and 59.

A rearwardly opening slot 68, Fig. 8, is formed in the ear 58 for reception of the portion of the bolt 61 disposed between the head thereof and the cam disc 64, Figs. 3 and 4. The lengths of the brackets 51 and 52 and the bolt 61 are such that when the brackets 51 and 52 are disposed in closed position and the latching member 53 is disposed in released position, as shown in Fig. 4, and as will be discussed in greater detail presently, the head end of the bolt 61 may readily be slipped forwardly and rearwardly, into and out of the slot 68 in the ear 58, the brackets 51 and 52 being sufficiently flexible to permit the necessary movement of the free ends thereof.

An elongated slot or notch 67, Figs. 1, 2 and 3, is formed in the central portion of the cover member 25 in position wherein, when the cover member is disposed on the ledges 44 in operative position to close the opening 23, and the brackets 51 and 52 are disposed in the closed position shown in solid lines in Figs. 3 and 4, with the bolt 61 disposed in the slot 68 in the ear 58, the slot 67 is disposed directly below the cam disc 64, in longitudinal alignment therewith.

Upon initial movement of the brackets 51 and 52 from outwardly disposed, or open position, shown in broken lines in Fig. 3, to the closed position shown in solid lines in Fig. 3, wherein the bolt 61 is disposed in the slot 68, the latching member 53 is disposed in the released position shown in solid lines in Figs. 4 and 7. However, thereafter, by turning the handle 65, the latching member 53 may be turned from released position to the latched position shown in solid lines in Figs. 2 and 3 and in broken lines in Fig. 7. It will be noted that, when the latching member 53 is disposed in the aforementioned latched position, the lower edge portion of the cam disc 64 is disposed in the slot 67 in the cover 25 and presses firmly downwardly on the central portion of the cover 25 to thereby firmly hold the cover 25 in sealed relation to the ledges 44 defining the opening 23. The slot 67 is preferably of substantially the same width as the cam disc 64, being only sufficiently wider to freely receive the lower end portion of the cam disc 64, and, therefore, affords an effective guide slot for the cam disc 64.

The latching member 53 and the brackets 51 and 52 are so constituted and arranged that: when the brackets 51 and 52 are disposed in closed position but the latching member is dis-

posed in released position, as shown in Fig. 4, the latching member 53 is suspended from the bolt in slightly spaced relation to the cover 25, whereby, substantially no tension is placed on the bolt 61 and, therefore, the bolt 61 may be readily slipped into and out of the slot 68 in the ear 58; but, when the brackets 51 and 52 are disposed in closed position and the latching member 53 is disposed in latched position, as shown in solid lines in Fig. 3, the inner end portions of the resilient brackets 51 and 52 are sprung upwardly by the pressure of the latching member 53 on the cover 25, and the retainer 26 is thereby effective to spring-urge the cover 25 into firm seating relation to the ledges 44. Adjustment of the tension of the brackets 51 and 52 may be made by tightening or loosening the bolt 61 in accordance with whether a greater or lesser amount of tension, respectively, is desired.

Removal of the cover 25 from latched position on the body member 22 may be readily effected by first swinging the latching member 53 from the latched position shown in broken lines in Fig. 8 to the released position shown in solid lines therein, to thereby release the tension on the brackets 51 and 52; then deflecting the bracket member 52 rearwardly to remove the bolt 61 from the slot 68; then swinging the brackets 51 and 52 upwardly from the closed position shown in solid lines in Fig. 4 to the open position shown in broken lines in Fig. 3; and then lifting the cover 25 from the ledge 44. When desired, the cover 25 may again be disposed in latched position by reversing the aforementioned procedure. Thus, it will be seen that the cover 25 may be quickly and easily moved into and out of latched position, and, when the cover 25 is mounted in latched position, the brush holder 20 comprises a relatively small, compact unit, which may be readily carried in a painter's hand, or in his pocket or tool kit.

As is best seen in Fig. 2 the lower face 81 of the cover member 25 slants downwardly from a position somewhat rearwardly of the longitudinal center thereof to the front edge thereof, and the front end portion 82 of the bottom wall 28 slants upwardly from a position somewhat rearwardly of the longitudinal center thereof to the front edge thereof. The tapering of the bottom face 81 of the cover member 25 and the end portion 82 of the bottom wall 28 is preferably such that the inner surfaces of these end portions of the cover member 25 and the bottom wall 28 assume substantially the natural position of the respective, opposite, outer flat surfaces of the bristles PB of the brush B and afford clamping members for firmly holding the bristles PB of a brush B in natural position therebetween, when the brush B is mounted in stored position in the holder 20. Thus, it will be seen that, with the cover member 25 disposed in latched position on the body member 22, the inner face 81 of the cover member 25 and the end portion 82 of the bottom wall 28 compress the bristles PB of the brush B therebetween and insure that the bristles PB will be held in the aforementioned natural position.

In the operation of the novel paint brush holder 20, shown in Figs. 1 to 8, inclusive, the cover member 25 may be removed from the body member 22. Thereafter a paint brush, such as the paint brush B may be inserted, handle first, into the opening 23, the handle H being inserted into the handle portion 41 of the body member 22 and the body P of the brush B then dropped into the head portion 42 of the body member 22. The

internal shape and dimensions of the body member 22 are preferably such that, when the brush B is disposed in operative position therein the inner surfaces of the body member 22 are disposed in relatively close-fitting relation thereto, to thereby insure that the brush B is retained in proper stored position therein.

If desired, after the brush B has been placed in the body member 22, a small amount of a suitable preserving or cleansing fluid such as, for example, turpentine, may be poured into the body member 22. Thereafter the cover 25 may be placed in position in the opening 23 at which time, it will be seen that the end portion 81 of the inner surface of the cover member 25 rests on the bristles PB of the brush B.

The brackets 51 and 52 may then be swung from the open position shown in dotted lines in Fig. 3 into the closed position shown in solid lines in Fig. 4, and the bolt 61 slid into the slot 68 in the ear 53, the latching member 53 being disposed in released position during this movement of the brackets 51 and 52. The operator, may then, by manipulating the handle 65 on the latching member 53 rotate the cam disc 64 from the released position shown in Fig. 4 to the latching position shown in Figs. 2 and 3, at which time, the cam disc 64 engages in the notch 67 and presses downwardly firmly on the central portion of the cover member 25 to thereby firmly seat the peripheral edge portions of the cover member 25 on the gasket 73 mounted on the supporting ledges 44. This downward pressure on the cover member 25 presses the end portion 81 of the inner surface of the cover member 25 into firm engagement with the bristles PB to thereby yieldingly, but firmly, clamp the bristles PB between the end portion 81 of the lower surface of the cover member 25 and the end portion 82 of the bottom wall 28 of the body member 22. With the cover 25 disposed in this position, it will be seen that the holder 20 affords a practical and novel storing receptacle for the paint brush B wherein the paint brush B is sealed in the holder 20 and is clamped between the cover member 25 and the bottom wall 28 in a manner to preserve the desired shape of the bristles PB.

Also, it will be seen that the holder 20 affords a practical carrying case for the paint brush B which may be readily carried in the pocket of a workman, and which is effectively sealed to insure against the spilling or evaporation of preservative liquid carried in the body member 22 to preserve the flexibility and pliability of the bristles PB. Such a device, it will be seen, affords a novel and practical holder for permanently storing cleaned brushes for prolonged periods of time, the cleansing agent, sealed in the holder being effective to maintain such a brush in the desired, pliable condition. Also, it has been found that my novel device affords a novel, efficient holder for temporarily storing paint brushes between jobs for relatively short periods such as, for example, over-night or for a day or two without cleaning. For example, it has been found that if it is necessary that a painter quit temporarily, such as over-night, before a painting job is completed, the uncleaned paint brush may be placed in my novel holder, a few ounces of turpentine placed in the holder, and the cover sealed in closed position, and the brush will be maintained in soft, pliable condition so that the next day it may be removed from the holder and immediately used in continuing the painting job.

Normally, when it is desired to clean out the

body member 22 of the brush holder 20, it is only necessary to pour a suitable cleaning fluid, such as, turpentine, alcohol, or the like, into the body member 22 and rinse the body member 22 thoroughly. However, in some instances and especially if the holder 20 has been mistreated and paint has been permitted to dry on the interior thereof, it may be desirable to have unrestricted access to the relatively narrow handle portion 41 of the body member 22 and for this purpose I prefer to embody the top wall 35 as a removable member of the body member 22. In this connection, it will be seen that in the event that it is desired to do so, the screws 37 may be removed from the top wall 35 and the top wall 35 may then be completely removed from the body member 22 to thereby afford ready access to the interior of the handle portion 41 of the body member 22 for cleaning purposes, or the like.

From the foregoing, it will be seen that the preferred form of my novel brush holder, as shown in Figs. 1 to 8, inclusive, affords a brush holder which provides a novel storing receptacle for paint brushes and the like; provides a novel and practical carrying case for paint brushes and the like; provides a device wherein not only the soft texture and pliability of the bristles may be readily preserved, but also affords a device which preserves the desired shape and form of the bristles of a paint brush; and provides a novel paint brush holder wherein the cover may be removed quickly and easily, and, when mounted in operative position on the body member, is yieldingly held thereon in a novel and expeditious manner which insures that the cover member will be properly disposed in sealed relation to the body member.

It will be seen that although the spring-urging of the cover member 25, from the center thereof, insures proper seating of the cover 25 in sealing relation to the ledge 44, and forms an important aspect of my invention, it is only one aspect thereof and that other means for holding the cover member of my novel device in proper closed relation to the body member thereof may be used without departing from the spirit of my invention.

In Figs. 9 to 15, inclusive, a modified form of my invention is shown which is constructed and operates on the same principle as the preferred form of the brush holder shown in Figs. 1 to 8, inclusive, and like reference numerals have been used on like parts and the same reference numerals, with the suffix "a" added thereto, have been used on parts which are similar, but which have been substituted for parts of the preferred form of my brush holder. All of the changes made in the modified form of my invention over the preferred form, as shown, are embodied in the top wall 35a of the body member 22a, the central portion of the cover member 25a, and the retainer 26a, as will be discussed in greater detail presently.

It will be noted that the changes made in the modified form of my invention, comprise the following: the top wall 35a of the body member 22 is not formed as a separate part but is an integral part of the body member 22, formed integrally with the side walls 32 and 33 and the end wall 30; the upper surface of the cover member 25a has been changed to eliminate the slot 67, and to include a boss 101 projecting upwardly from the central portion of the top surface of the cover member 25a and having a groove 102 extending

transversely across the upper face thereof; and a spring-clip type of latching member 53a has been substituted between the brackets 51 and 52 in place of the eccentrically mounted cam-plate type of latching member 53, embodied in the preferred embodiment of my invention shown in Figs. 1 to 8, inclusive. No claim is made to the spring-clip latching member 53a except as it forms a part of my novel combination.

The latching member 53a comprises an elongated piece of suitable material, such as, for example, wire or spring steel having one end portion thereof bent to form a substantially U-shaped handle 105, having a loop 107 formed on the free end portion of one leg 106 and through which loop 107 the bolt 61 extends. The other leg 108 is normally disposed directly below the leg 106 and the free end portion thereof is bent to form a substantially semi-circular shaped latching jaw 110, Figs. 12 and 15. In forming the latching jaw 110, the free end portion of the leg 108 is bent to form, successively, an arcuate-shaped rear leg 114 projecting from the handle 105, a cross-bar 112, and another arcuate-shaped rear leg 115 extending from the cross-bar 112 toward the handle 105, the free end portion of this latter rear leg 115 of the latching jaw 110 terminating adjacent to the junction of the first mentioned rear leg 114 with the handle 105.

In the operation of the brush holder 20a shown in Figs. 9 to 15, inclusive, the cover member 25a may be disposed in operative position in the opening 23, with the brackets 51 and 52 disposed in the open position shown in dotted lines in Fig. 11. Thereafter the brackets 51 and 52 may be swung into the closed position shown in solid lines in Fig. 11 in the same manner as previously discussed with respect to the retainer 26. After movement of the brackets 51 and 52 into closed position the bolt 61 may be slid into the ear 58, at which time the latching member 53a is normally disposed in a position corresponding to that shown in dotted lines in Fig. 13, wherein the free end portion of the handle 105 is disposed toward the end 29 of the body member 22a and the cross bar 112 of the latching member is disposed in spaced relation above the boss 101 on the cover member 25a. To effect closing of the latching member 53a, the handle 105 may be swung in a clockwise direction, as viewed in Fig. 13 from the dotted line position shown in Fig. 13 to the position shown in solid lines in Figs. 14 and 15, wherein the cross-bar 112 is engaged in the groove 102 in the boss 101, and then swung further to the closed position shown in solid lines in Fig. 13.

It will be seen that during this closing movement of the handle 105, the cross bar 112 is swung downwardly into position in the groove 102 in the boss 101 and, by the continued closing movement of the handle 105, is latched in yieldingly, downwardly pressing engagement with the top of the boss 101, the bolt 61 swinging past the dead-center position of the cross bar 112 in a clockwise direction to thereby firmly hold the cross bar 112 in latched position until the handle 105 may be turned manually in a counter-clockwise direction from the aforementioned latched position toward the aforementioned unlatched position.

As in the preferred form of my invention, it will be seen that with the cover member 25a removed from the body member 22a, a paint brush may be readily inserted through the opening 23 into the storage chamber defined in the body 75

member 22a, the handle of the paint brush being inserted in the handle portion 41a of the body member 22a and the head of the paint brush then being dropped into the head 42 of the body member 22a. When it is desired to release the cover 25a from the body member 22a and remove a paint brush stored therein, it will be seen that this may be readily accomplished by swinging the handle 105 of the latching member 53a from the latched position shown in solid lines in Fig. 13 to the unlatched position shown in broken lines therein. Thereafter, the bolt 61 may be slid rearwardly out of the slot in the ear 58 and the brackets 51 and 52 may then be swung upwardly into the open position shown in broken lines in Fig. 11, and the cover member 25a may then be readily lifted from the body member 22a.

Thus, it will be seen that, like the preferred form of my invention, the modified form of my invention affords a compact brush holder wherein a brush may be sealed in a novel and expeditious manner, and wherein a brush may be mounted in, and removed from the holder quickly and easily.

From the foregoing, it will be seen that I have provided a novel paint brush holder which affords a novel storing receptacle and carrying case for paint brushes and the like, and which, when a paint brush is stored therein, is effective to hold the paint brush in a novel and expeditious manner to thereby hold the bristles thereof in their preferred shape.

Also, it will be seen that I have provided a novel paint brush holder wherein a paint brush may be stored and preserved with cleaning fluid such as, for example, turpentine and which holder may be readily carried in the pocket of a workman to act as a carrying case for such a paint brush.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. A brush holder for paint brushes of the type having a handle, and bristles projecting from the handle, said brush holder comprising a body member having substantially the contour of one of said brushes and having four sides and two ends and having a chamber within which an entire one of said brushes may be disposed in stored position, two of said sides being wider than the other two sides, said body member having edge portions defining an opening on one of said wider sides through which said brush may be inserted into, and withdrawn from, said body member, a cover member mounted in operative position on said body member in abutting relation to said edge portions to close said opening, and means releasably clamping said cover member in said operative position in sealed relation to said body member, said cover member having a flat outer surface and gradually increasing in thickness toward one end thereof from the mid-portion thereof and cooperating with the opposite wall of said body member to form a wedge-like chamber at one end of the body member for holding said bristles in flat compact relation to each other.

2. A brush holder for paint brushes, and the like, said holder comprising a body member hav-

11

ing a chamber for receiving such a paint brush therein, said chamber being substantially complementary in shape and size to said paint brush, said body member having an opening therein, in communication with said chamber and the outside of said body member through which such a brush may be inserted into, and removed from said chamber, a cover member removably mounted in operative position on said body member for closing said opening, said cover member including an abutment member projecting outwardly from the central portion thereof, and means for releasably holding said cover member in said operative position on said body member, said means comprising a retaining member mounted on said body member and extending across said cover member, and a latching member pivotally mounted on said retaining member and movable into and out of latching engagement with said abutment member, said latching member comprising a substantially U-shaped spring-clip member having one leg pivotally mounted on said retaining member for swinging the other leg of said spring clip member downwardly and upwardly, into and out of latching engagement with the top of said abutment member, said latching member when disposed in said latching engagement with said abutment member being operable to yieldingly press said cover member into engagement with said body member.

3. A holder for storing and carrying paint brushes, and the like, in stored position therein, said holder comprising an elongated body member including a bottom wall having a relatively narrow handle-forming portion at one end thereof, and an enlarged head-forming portion at the other end thereof, said body member also including a continuous side wall projecting upwardly from the outer peripheral edge portion of said bottom wall, and a top wall mounted on said side wall at said one end of said bottom wall in substantially parallel spaced relation to said bottom wall and closing the top of one end of said body member, said top wall projecting toward, and terminating in spaced relation to, the portion of said side wall projecting upwardly from said other end of said bottom wall, a cover member movably mounted in operative position on said side wall and said top wall in position to close the top of the other portion of said body member not closed by said top wall, said cover member being movable from said operative position to thereby open said top of said body member to permit the insertion of such a paint brush into said stored position in said body member with the handle of said paint brush disposed in juxtaposition to said handle-forming portion of said bottom wall and the head of said paint brush disposed in juxtaposition to said head-forming portion of said bottom wall, and means for releasably holding said cover member in said operative position on said side wall and said top wall.

4. The holder defined in claim 3 and in which said cover member and said head-forming portion of said bottom wall include portions disposed in position relative to each other, when said cover member is mounted in said operative position on said side wall and top wall, to clampingly engage said head of such a paint brush disposed in said stored position in said body member.

5. A holder for storing and carrying paint brushes, and the like, in stored position therein, said holder comprising an elongated body member including a bottom wall having a relatively narrow handle-forming portion at one end there-

12

of and an enlarged head-forming portion at the other end thereof, said body member also including a continuous side wall projecting upwardly from the peripheral edge portion of said bottom wall, and a top wall mounted on said side wall at said one end of said bottom wall in substantially parallel spaced relation to said bottom wall and closing the top of one end of said body member, said top wall projecting toward, and terminating in spaced relation to, the portion of said side wall projecting upwardly from said other end of said bottom wall, a cover member movably mounted in operative position on said side wall and said top wall in position to close the top of the other portion of said body member not closed by said top wall, said cover member being movable from said operative position to thereby open said top of said body member to permit the insertion of such a paint brush into said stored position in said body member with the handle of said paint brush disposed in juxtaposition to said handle-forming portion of said bottom wall and the head of said paint brush disposed in juxtaposition to said head-forming portion of said bottom wall, said bottom wall and said cover member having oppositely disposed inwardly facing surfaces tapering toward each other in a direction toward said other end of said bottom wall in position to clampingly engage the bristles of said brush therebetween when said cover member is disposed in said operative position on said body member, and means for releasably holding said cover member in said operative position on said body member.

35 6. A holder defined in claim 5 and in which said means for releasably holding said cover member comprises an elongated bale extending across said cover member and having opposite ends thereof connected to oppositely disposed portions of said side wall, and a latching member pivotally mounted on said bale in the central portion of said bale, said latching member being rotatable on said bale into and out of latching position, wherein said latching member is disposed in downwardly-pressing engagement with the central portion of said cover member.

7. A holder for paint brushes of the type having a handle at one end, and an enlarged head at the other end, the free end portion of said head comprising a plurality of bristles normally disposed in substantially flat, compact relation to each other, said holder comprising a body member comprising an elongated bottom wall having one end portion disposed at an upwardly projecting angle to the other end portion thereof, side walls projecting upwardly from the peripheral edge portions of said bottom wall to define an elongated area substantially complementary in size and shape to such a brush, and a top wall mounted on said side walls and closing the top of one end portion of said area, a cover member removably mounted in operative position on said side walls in sealing engagement with said side walls and said top wall for closing the other portion of the top of said area not closed by said top wall, said cover member being removable from said operative position to thereby open said other portion of said top of said area to thereby afford an opening for inserting and removing said brush into and out of stored position in said area, said cover member having one end portion disposed substantially opposite said one end portion of said bottom wall when said cover member is disposed in said operative position, said one end portion of said cover member having an inner

face projecting downwardly at an acute angle toward said one end portion of said bottom wall, said inner face of said one end portion of said cover member and said one end portion of said bottom wall being disposed in position relative to each other, when said cover member is disposed in said operative position, to clampingly engage said bristles of such a brush disposed in said stored position in said body member and thereby positively hold said bristles in said normally disposed relation to each other, and means mounted on said body member and releasably engaged with said cover member for releasably holding said cover member in said operative position on said body member.
